(57) **CLAIM**

The ornamental design for a splattering fender for frypan, as shown and described.

DESCRIPTION

FIG. 1 is a perspective view of a first embodiment of a splattering fender for frypan, showing the new design; FIG. 2 is a front view of the splattering fender for frypan of FIG. 1, a rear, left or right view thereof is the same as the front view;

FIG. 3 is a top plan view of the splattering fender for frypan of FIG. 1;

FIG. 4 is a bottom plan view of the splattering fender for frypan of FIG. 1;

FIG. 5 is a cross-section view of the splattering fender for frypan of FIG. 1, showing contours thereof; and

FIG. 6 is a perspective view of the splattering fender for frypan of FIG. 1 in use with cookware.

FIG. 7 is a perspective view of a second embodiment of the splattering fender for frypan, showing the new design;

FIG. 8 is a front view of the splattering fender for frypan of FIG. 7, a rear, left or right view thereof is the same as the front view;

FIG. 9 is a top plan view of the splattering fender for frypan of FIG. 7;

FIG. 10 is a bottom plan view of the splattering fender for frypan of FIG. 7;

FIG. 11 is a cross-section view of the splattering fender for frypan of FIG. 7, showing contours thereof; and,

FIG. 12 is a perspective view of the splattering fender for frypan of FIG. 7 in use with cookware.

The broken lines are employed to show environmental structure the splattering fender for frypan might be used with, and form no part of the claimed design.

1 Claim, 12 Drawing Sheets
